(57) **CLAIM**

The ornamental design for a ground lamp, as shown and described.

DESCRIPTION

FIG. 1 is a first perspective view of a ground lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 2.

The evenly spaced broken lines shown in the drawings depict portions of the ground lamp that form no part of the claimed design. The long-dash-short-dash broken line circles in FIGS. 1, 2, 9, and 10 define the bounds of the enlargements and do not form part of the claimed design.
